J. T. DOWDALL.

SPool SUPPORT.

APPLICATION FILED SEPT. 13, 1918.

1,315,764.

Patented Sept. 9, 1919.

UNITED STATES PATENT OFFICE.

JAMES T. DOWDALL, OF WOODHAVEN, NEW YORK, ASSIGNOR OF ONE-HALF TO MORRIS FRIEDMAN, OF NEW YORK, N. Y.

SPOOL-SUPPORT.

1,315,764.

Specification of Letters Patent.

Patented Sept. 9, 1919.

Application filed September 13, 1918. Serial No. 253,899.

To all whom it may concern:

Be it known that I, JAMES T. DOWDALL, a citizen of the United States of America, residing at Woodhaven, Queens county, New York State, have invented certain new and useful Improvements in Spool-Supports, of which the following is a full, clear, and exact description.

This invention relates to spool-holders for sewing machines. My invention is directed toward the provision of an efficient support for spools of thread, such as are used for manufacturing garments or the like in large quantities. Sewing thread for the above named purpose is supplied in the form of large spools or cops in the form of a conical spool. It is quite essential that thread for machines which are operated at high speed should be reeled off the spools or cops easily and without danger of catching. My improved holder is designed to stand upon or be supported over the table of a sewing machine and may be placed in a position best suited to obtain good results.

A further object of the invention is to provide a holder that can be adjusted to spools or cops of various sizes, and also one that can be cheaply manufactured.

Other features of improvement will be pointed out in the following specification and illustrated in the accompanying drawing, wherein:

Figure 1 is a side elevation of my improved spool holder;

Fig. 2 is an enlarged cross-sectional view taken on a line 2—2 in Fig. 1;

Fig. 3 is a diagrammatic detail view illustrating the manner of supporting a spool of thread;

Fig. 4 is a similar view illustrating the manner of supporting a cop or conical spool of thread; and

Fig. 5 is a fragmentary side elevation of a modified form of holder.

As herein embodied my invention comprises a block or body member 6 to which the spool or cop engaging arms or members are connected. The spool or cop engaging arms are indicated by 7 and 8 and are secured at one end thereof, to angle members or frames 9 and 10, respectively, the frame members 9 and 10 being engaged by a rotatable operating spindle 11 provided with right-hand threads 12, and left-hand threads

13 engaging threaded openings 14 and 15, respectively, in the frames 10 and 9, respectively. The spindle 11 is rotated by means of a handle 16, and will, when rotated, cause the arms 7 and 8 to approach or recede one from the other, a pin 17 being utilized to slidably engage the frames 7 and 8 and prevent the rotation thereof when the spindle 11 is rotated to adjust the arms 7 and 8 to engage a spool such as is indicated by 18 in Fig. 3, or a conical cop indicated by 19, Fig. 4.

To rotatably support the spindle 11 and also to prevent longitudinal movement thereof, I provide the same, intermediate its ends, with an annular recess 20 (Fig. 2) which is engaged by a tap-bolt 21. The tap-bolt prevents the spindle from premature removal from the block 6 and at the same time permits the spindle to be rotated.

To grip the core of the spool or cop, I provide the outer end of each arm 7 and 8 with a tooth 22 sharp enough to engage or slightly enter the core of the spool or cop.

In combination with the spool or cop holder, I provide a thread guide 23 having an eye 24 alining with the axis of the block 6. The thread guide is adjustably supported by a post 25 carried by the block 6 of the spool or cop-holder, a set screw 26 serving to maintain the guide 23 in adjusted positions. The holder and thread-guide are supported by a standard (in this instance) indicated by 27, said standard being provided with a base 28 to enable it to be maintained upon a table of a sewing machine in an upright position relative to the machine proper.

The frame members 9 and 10 not only support the arms 7 and 8, but also serve to act as a backing for a spool or cop, particularly a cop as illustrated in Fig. 4.

As the core of these cops is tapered it would be difficult to support them in a horizontal position,—a position which is desirable for the unreeeling of the thread,—unless some means is used to maintain them in said position while the arms or clamping members are being adjusted or applied thereto.

To mount a spool or cop it is but necessary to operate the spindle 11 to cause the arms or clamps 7 and 8 to come together, after which the spool or cop is placed over the

said arms or clamps and forced against the frames 9 and 10, as illustrated in Fig. 4. The frames 9 and 10 form the base of the clamp as a whole, and the axes of the arms 5 9 and 10 are located at a right angle to that portion of said frames against which the spool or cop is forced; hence after the spindle 11 is operated to move the arms 7 and 8 apart to grip the core of the spool or cop, 10 the said spool or cop will be maintained in a horizontal position, the backing provided by the frames 9 and 10 serving to aid in the maintenance of said position. By means of the above arrangement, the axis of the spool 15 or cop will be maintained in line with the axis of the block 6.

The above described arrangement of parts is particularly well adapted for cops or conical spools of thread. Instead of providing 20 two movable arms I may provide the block 6 with a fixed arm 29 Fig. 5 and an arm 30 carried by a movable frame 31 which in turn is actuated by a threaded spindle 32, a pin 33 serving to guide the frame 31. Even in 25 this latter form I prefer to provide the fixed arm 29 with a backing or base member 34 positioned at a right angle to its axis.

It will be understood that each frame 9 or 10 with connected arms 7 or 8 may be made 30 integral instead of being separable members.

What I claim as my invention is:—

1. A spool-holder consisting of a plurality of angular frame members, a support there-

for, a threaded spindle rotatably mounted on said support and engaging said frames, 35 a guide pin also carried by the support and slidably engaging said frames, and an arm carried by each frame, the axis of each arm being at a right angle to that portion of its frame to which it is attached, for the purpose set forth.

2. A spool-holder comprising a support, a block, angular frames movably associated therewith, spool-engaging arms projecting from the frames, a rotatable operating spindle in threaded engagement with the said frames and arranged to cause the arms thereon to approach or recede one from the other, and a guide-pin in slidable engagement with the angular-frames. 50

3. A spool-holder comprising a support, a block, angular frames movably associated therewith, spool-engaging arms projecting from the frames, a rotatable operating spindle in threaded engagement with the said frames and arranged to cause the arms thereon to approach or recede one from the other, a guide-pin in slidable engagement with the angular-frames, and means to lock the spindle against longitudinal movement. 60

Signed at New York city, N. Y., this 11th day of September, 1918.

JAMES T. DOWDALL.
